UNITED STATES PATENT OFFICE

2,610,440

SPINNING TOP

Joseph J. Manske, Lester J. Martin, and Raymond J. Bernake, Milwaukee, Wis.

Application March 6, 1947, Serial No. 732,714

2 Claims. (Cl. 46—65)

1

This invention appertains to toys and more particularly to a novel spinning top.

One of the primary objects of our invention is to provide a pair of independent spinning tops, so arranged and constructed that one of the tops can be spun upon the other top during the spinning thereof so as to produce a new and novel effect.

Another salient object of our invention is to provide means for spinning a lower top and means for spinning an upper top and for placing the last named top on the lower top while the same is spinning.

A further object of our invention is to provide a novel frame or holder for supporting one of the tops during the initial spinning thereof, said frame or holder being so constructed that the spinning top can be quickly released and accurately deposited on a desired spot, such as a bottom spinning top.

A further important object of our invention, is to provide a pair of independent tops, with means for independently spinning each top, one of the tops (the lower top) being provided with concavo-convex disc at its upper end for receiving the axle or point of the other top.

A still further object of our invention is to provide a novel spinning top toy which will be durable and efficient in use, one that will be simple and easy to manufacture and one which can be placed upon the market at a reasonable cost.

With these and other objects in view the invention consists in the novel construction, arrangement and formation of parts as will be hereinafter more specifically described, claimed, and illustrated in the accompanying drawing, in which drawing

Figure 1 is a side elevational view illustrating the lower top of our novel toy and the holder thereof during the initial spinning thereof, parts of the view being shown broken away and in section to illustrate structural detail.

Figure 2 is a top plan view of the lower top and its holder showing the position thereof ready for spinning.

Figure 3 is a side elevational view of the upper top of our toy and the novel holder therefor for facilitating the initial spinning thereof and the depositing of the upper top on the lower top, parts of the figure being shown broken away and in section.

Figure 4 is a top plan view of the upper top and its novel holder for facilitating the spinning and depositing thereof.

Figure 5 is a front elevational view of the upper spinning top and the novel holder therefor.

2

Figure 6 is a detail sectional view through the holder taken on the line 6—6 of Figure 3 looking in the direction of the arrows.

Figure 7 is a view similar to Figure 5, but showing the support for the upper top moved to its released position with the top being placed on the lower spinning top.

Figure 8 is a fragmentary detail side elevational view illustrating a modified form of holder for the upper top, the view being taken on a smaller scale than the other views of the drawing; parts of the view being shown broken away and in section.

Referring to the drawings in detail, wherein similar reference characters designate corresponding parts throughout the several views, the letter T generally indicates our novel spinning top toy and the same includes a bottom spinning top 10 and an upper spinning top 11. A holder 12 is provided for facilitating the spinning of the lower top 10 and a novel holder 13 is provided for facilitating the spinning and depositing of the upper top 11.

The bottom top 10 includes a top body 14 having a centrally disposed axle 15 and the lower end of the axle is provided with a spinning point 16. The axle extends entirely through the top body and protrudes beyond the upper and lower ends thereof. The extreme upper end of the axle 15 is provided with a concavo-convex disc 17 and communicating with the axle center of this disc is a bore 18 which is formed in the axle 15. The portion of the axle 15 between the body 14 and the disc 17 provides a sleeve or drum around which the spinning cord 19 can be wound.

To facilitate the spinning of the lower top 10 we provide the holder 12. This holder 12 can be formed in any desired way and from out of any desired material.

In the present instance, we have shown the handle 12 formed from a length of wire and this wire is bent back upon itself to form a handle 20. The forward end of the holder is bent at right angles to provide a shaft 21, which is adapted to be inserted within the bore 18.

In spinning the lower top 10, the handle 20 of the holder is grasped in one hand and the shaft 21 is inserted in the bore 18. The spinning cord 19 is wound around the axle 15 after which the point 16 is placed upon the desired surface. The cord 19 can now be given a quick pull which would impart a spinning action to the top 10. The holder 12 can now be removed from the top.

The upper top 11 is constructed somewhat similar to the lower or bottom top 10; hence, the upper top 11 includes a top body 22. Extending

centrally through the body 22 is the axle 23 and this axle protrudes above and below the body. The lower end of the axle is provided with a spinning point 24. The upper end of the axle is provided with a centrally disposed bore 25. That portion of the axle 23 which protrudes above the body 22 is adapted to have wound thereabout the spinning cord 26.

The holding and releasing device 13 for the top 11 preferably includes a rod 27 having formed thereon or secured thereto a hand grip 28. The forward end of the rod 27 is bent downwardly at right angles to provide a shaft 29 which is adapted to be detachably inserted within the bore 25 of the top axle 23. This shaft 29 holds the top centered and permits the initial spinning thereof. To facilitate the lifting, spinning and releasing of the top, we provide a swinging frame 30. This frame 30 consists of a straight body portion 31 which extends parallel to the rod 27 and one end of the body portion has formed thereon a depending holding arm 32. The forward end of the body portion 31 has formed thereon a depending bearing arm 33. The supporting arm 32 and the bearing arm 33 are provided with aligned bearing openings for receiving the rod 27. Formed on the bearing arm 33 is a laterally extending stop lug 34 which is adapted to engage one side of the shaft 29 to limit the rocking movement of the frame on the rod 27. The lower end of the supporting arm 32 is curved forwardly to provide a supporting foot 35 and this foot extends under and supports the lower end of the top axle 23 when the shaft 29 is inserted in the bore 25. The supporting foot 35 is normally held under the top 11 with the stop lug 34 in engagement with the shaft 29 by a spring 36. This spring 36 is coiled about the rod 27 between the supporting arm 32 and the bearing arm 33. One end of the spring bears against the shaft 29 and the other end of the spring bears against a thumb piece 37 formed on the body portion 31 of the frame 30. In use of the support and releasing device 13 the hand grip 28 is grasped in one hand by the operator and downward pressure is exerted on the thumb piece 37. This will swing the frame 30 laterally with the foot 35 to one side of the shaft 29. The top 11 is now taken in the other hand and the shaft 29 is inserted in the bore 25. Pressure is released from the thumb piece 37 and the supporting foot 35 engages under the spinning point 24 and supports the top. The spinning cord is now wound around the axle 23 and this cord can be given a sharp pull so as to give the top 11 the desired spinning action. If the bottom top 10 has already been given its spinning action and the handle 12 removed therefrom, the top spinning top 11 can be moved over the bottom top with the spinning point 24 directly above the concavo-convex disc 17. Pressure can now be exerted on the thumb piece so as to move the foot away from the spinning point 24 and the top 11 will fall by gravity toward the bottom top 10 and the spinning point will engage the concavo-convex disc 17 and spin therein.

This gives a novel effect and gives a child a maximum amount of amusement.

In Figure 8 we have shown a modified form of holder and releasing device for the top 11. In this form the axle 23 of the top 11 is provided with an annular bearing groove 38, the purpose of which will later appear. Cooperating with the top is the modified form of holder and re-

leasing device 39 and this device can be formed from wire and includes a straight body portion 40. Formed on the forward end of the straight body portion is the depending right angularly disposed shaft 41 which is adapted to be freely inserted within the bore of the top axle 23. The rear end of the body portion 40 is bent back to form a handle 42 and a guide arm 43. The guide arm is arranged in spaced parallel relation to the body portion 40. Slidably mounted upon the body portion 40 and the guide arm 43 is an inverted U-shaped frame 44 and this frame can be slid back and forth on the body portion of the arm. The forward end of the frame 44 has formed thereon a forwardly extending bifurcated leg 45 and this leg is adapted to engage in the annular groove 38 and support the axle 23. Considering that the frame is supporting the axle and that the shaft 41 is in the bore of the axle, then the spinning cord can be wound around the axle and pulled to spin the top. After the top is spun, the frame is pulled back with the finger so as to disengage the leg 45 from the axle and the top can then be dropped on the surface or on the spinning top.

Changes in details may be made without departing from the spirit or the scope of our invention, but what we claim as new is:

1. In a toy, a spinning top having an axle provided with a bore, and a support and releasing device for the top including a handle, an arm extending forwardly of the handle, a depending shaft on the arm removably received in said bore, a frame laterally rockably mounted on the arm including a supporting foot normally disposed under the top for engaging the spinning point of the top, and means for rocking the frame to move the supporting foot from under the spinning point.

2. In a toy, a spinning top including an axle having a bore, a supporting and releasing device for the top during the initial spinning thereof including a rod, a handle on one end of said rod, a depending shaft on the other end of said rod receivable in said bore, a frame rockably mounted on the rod including a leg normally deposited under the spinning point of the top, spring means normally urging the frame and its leg to one position with the leg under the top, and means for rocking the frame and its leg against the tension of spring means to move the leg from under the top.
